UNITED STATES PATENT OFFICE.

FORREST R. MAGUIRE, OF PITTSBURGH, PENNSYLVANIA, ASSIGNOR, BY DIRECT AND MESNE ASSIGNMENTS, TO MAGUIRE MANUFACTURING COMPANY, OF PITTSBURGH, PENNSYLVANIA.

INSECT-BEATER.

1,150,690.

Specification of Letters Patent. Patented Aug. 17, 1915.

Application filed November 13, 1914. Serial No. 872,055.

To all whom it may concern:

Be it known that I, FORREST R. MAGUIRE, a citizen of the United States, residing at Pittsburgh, in the county of Allegheny and 5 State of Pennsylvania, have invented certain new and useful Improvements in Insect-Beaters, of which the following is a specification.

My invention consists of an improvement 10 in what is known in the art as a "fly swatter."

The device, as its name implies, is intended for the purpose of destroying flies or other insects by striking them against a wall or other flat surface. Ordinarily, such devices consist of a handle with an oval-shaped flat racket-shaped beater of thin 15 light material rigidly connected with the handle, and used in the manner indicated.

My invention is designed to provide a device 20 of this character in which the beater or swatting element is pivotally connected to the end of the handle, and so constructed as to provide a lever extension beyond its pivotal joint adapted to be brought into contact with the wall or ceiling surface, so as 25 to effect thrusting of the flat face of the beater directly and truly upon the flat surface and against the insect thereon.

One preferred construction of the invention 30 is illustrated in the accompanying drawings, in which—

Figure 1 illustrates the device in sectional elevation, partly broken away, and in position to operate against a wall surface. Fig. 35 2 is a rear view of the device in elevation. Fig. 3 is an enlarged plan view, showing the beater erected longitudinally of the handle. Fig. 4 is an edge view of Fig. 3 in elevation. Fig. 5 is a cross sectional detail view, on the 40 line V. V. of Fig. 4.

Referring to the drawings, the handle 2, which may be of any suitable material, and of any desired length, is provided with a pivotal mounting 3 at its operating end, as 45 by means of a pin or rivet extending through the handle from side to side closely adjacent to its outer end, as shown.

The beater, indicated generally by the letter B, is of any suitable form as to contour, 50 i. e., round or oval, and so constructed as to present a broad, flat, somewhat resilient surface as to its middle portion, within a surrounding comparatively rigid frame. As shown, the beater is formed of a loop of wire 55 4, bowed around to form an outer frame,

brought together at 5, and connected by its terminals 6, preferably slightly diverging, with the turned edges of a sheet metal frame 7. Said frame is rounded semi-cylindrically, or otherwise, to form a longitudinal 60 central double-sided extension, adapted to embrace the handle 2 at its pivotal mounting 3 rearwardly beyond the same a sufficient distance to provide a lever extension 8, having the double sides a, a. Said lever 65 extension is preferably provided with laterally extended somewhat inwardly disposed clamping ears or lugs 9, adapted to embrace beyond the maximum diameter of the handle 2, and to somewhat firmly hold the beater in 70 erected position, as in Figs. 3 and 4. At its rear terminal, the lever extension 8 is preferably provided with a slightly rounded bearing terminal 10 adapted to bear against the 75 wall surface, as in Fig. 1.

For the purpose of supporting the beater at a suitable angle upon the end of the handle 2, preparatory to utilizing it, I provide a bearing abutment 11 of any suitable construction, but preferably by means of a 80 partly slotted tongue or tang formed of the sheet metal of the frame 7 itself, which is adapted to bear against the side face of the handle 2, as in Fig. 1, to prevent the beater from collapsing backwardly against the 85 handle. The beater itself is provided with any suitable web or body b of wire mesh or other material, which may be connected with the wire frame 4 by any means, as a surrounding binding 12 of fabric or other suitable material stitched, glued, or otherwise secured to hold the web in position, and with 90 relation to the frame.

Various forms or constructions of the beater itself may be utilized, and I do not 95 desire to be specifically limited to the construction illustrated.

The operation will be readily understood from the foregoing description. The beater being loosened as to ears 9 from the handle, 100 is thrown back at the angle shown with relation to the handle and advanced toward the wall, ceiling or other surface, and the terminal 10 coming into contact therewith, forward movement of the handle thrusts 105 the beater at accelerated speed in the direction of the arrow (Fig. 1) flatly against the wall and the insect thereon.

The leverage exerted by the handle tends to greatly accelerate the speed, while the po- 110

sition of the beater itself as to meeting the wall flatwise is insured by proper positioning of the handle in operation.

If desired, the beater may be erected, as shown in the enlarged figures, and used in the ordinary way upon a table or floor surface, and its range of efficiency is thus very considerably increased.

It will be understood that the device may be changed or varied in detail construction or otherwise by the skilled mechanic, but that all such changes are to be considered as within the scope of the following claims.

What I claim is:

15 1. An insect beater consisting of a handle and a flat beating element having a longitudinal central double sided extension forming a continuation of the beating element in the same general plane thereof pivotally mounted on the extreme end of the handle and closely embracing and covering said end.

20 2. An insect beater consisting of a handle and a flat beating element having a longitudinal central double sided extension forming a continuation of the beating element in the same general plane thereof pivotally mounted on the extreme end of the handle, closely embracing and covering said end and provided with a movement limiting abutment adapted to engage the handle adjacent to said pivotal mounting.

25 3. An insect beater consisting of a handle and a flat beating element having a longitudinal central double sided extension forming a continuation of the beating element in the same general plane thereof pivotally mounted on the extreme end of the handle, closely embracing and covering said end and extending beyond said pivotal mounting and forming a lever.

40 4. An insect beater consisting of a handle and a flat beating element having a longitudinal central double sided extension forming a continuation of the beating element in the same general plane thereof, said extension being bent inwardly at the sides U-form in cross section and pivotally mounted on and closely embracing the extreme end of the handle and extending beyond said pivotal mounting and forming a lever.

45 5. An insect beater consisting of a handle and a flat beating element having a longitudinal central extension forming a continuation of the beating element in the same general plane thereof, said extension being bent inwardly at the sides and pivotally

50 mounted on the end of the handle and extending beyond said pivotal mounting and forming a lever and having handle embracing clips.

55 6. An insect beater consisting of a handle and a flat beating element having a longitudinal central extension forming a continuation of the beating element in the same general plane thereof, said extension being bent inwardly at the sides and pivotally mounted on the end of the handle and extending beyond said pivotal mounting and forming a lever and having handle embracing clips and a terminal rounded bearing.

60 7. The combination with a supporting handle, of a beater frame of curved sheet metal formed to embrace the handle and pivoted to the end thereof, extending at one side of such pivotal mounting and formed into a lever terminal, and at the other side of said mounting having a flat beater element incorporated therewith and extending 70 longitudinally in the general plane of the beater frame.

75 8. The combination with a supporting handle, of a beater frame of curved sheet metal formed to embrace the handle and pivoted to the end thereof, extending at one side of such pivotal mounting and formed into a handle-embracing lever terminal, and at the other side of said mounting having an extended straight flat beater 80 element, and a movement limiting abutment extending laterally from said frame adjacent the pivotal mounting adapted to engage the handle to support the beater at an angle thereto.

9. In an insect beater of the class described, the combination with a handle, of a flat beating element having a longitudinal central sheet metal extension forming a continuation of the beating element in the same general plane thereof pivotally mounted on the extreme end of the handle and provided with a bearing terminal extending beyond the pivotal mounting and a tongue 90 extending from said sheet metal extension 100 at the other side of said mounting adapted 105 to bear against the end portion of the handle and to limit the movement of the beating element on said pivotal mounting.

In testimony whereof I hereunto affix my 110 signature in the presence of two witnesses.

FORREST R. MAGUIRE.
